Ohio China Company, Monroe, Mich., a partnership composed of Ralph F. Knutti and Ernst J. Ronal

Application April 5, 1943, Serial No. 109,908

Term of patent 14 years

To all whom it may concern:

Be it known that I, Kenneth M. Gale, a citizen of the United States, residing at Zanesville, in the county of Muskingum and State of Ohio, have invented a new, original, and ornamental Design for a Cookie Jar or Like Vessel, of which the following is a specification, reference being had to the accompanying drawing, forming part thereof.

Fig. 1 is a front perspective view of a cookie
jar or like vessel showing my new design;

Fig. 2 is a rear perspective view;

Fig. 3 is a front perspective view of the body
portion only of the jar;

Fig. 4 is a front perspective view of the cover
portion only of the jar;

Fig. 5 is a top plan view of the body of the jar,
and

Fig. 6 is a bottom plan view of the jar cover.

I claim:

The ornamental design for a cookie jar or like vessel, substantially as shown.

KENNETH M. GALE.
